SAFETY DEVICE FOR GAS COMBUSTION APPARATUS

Filed Nov. 14, 1923

INVENTOR
Louis Hill,
BY *Walton Harrison*,
HHS ATTORNEY.

Patented Feb. 8, 1927.

UNITED STATES PATENT OFFICE.

LOUIS HILL, OF AKRON, OHIO.

SAFETY DEVICE FOR GAS-COMBUSTION APPARATUS.

Application filed November 14, 1923. Serial No. 674,628.

My invention relates to safety devices for gas combustion apparatus, and more especially to safety devices of simple construction and small size, used in connection with ordinary gas burners.

More particularly stated I seek to use a gas burner of ordinary construction, equipped with two separate valves for controlling the supply of gas to the burner, one of these valves being operated by hand and the other being operated by a very simple thermostatic apparatus and parts immediately associated therewith, in such manner that when the temperature of the burner is lowered sufficiently, said last mentioned valve is actuated so as to cut off the supply of gas to the burner.

Reference is made to the accompanying drawing forming a part of this specification, and in which like reference characters indicate like parts throughout the several figures.

Figure 1 is a plan view of a stove gas burner equipped with my device the various parts being in such condition that the flow of gas to the burner is cut off.

Figure 2 is a side elevation of the mechanism shown in Figure 1.

Figure 3 is a fragmentary plan, corresponding to a portion of Figure 1, but showing the apparatus as in such condition that gas is flowing freely to the burner.

A stove burner appears at 4, and is connected with a mixing tube 5. Leading into the mixing tube is a jet pipe 6, and this jet pipe is provided with two plug valves 7, 8.

The valve 7 has a handle 9 whereby it is operated. The valve 8 has a lever 10 whereby it is operated, this lever being provided with an upturned portion 11 to be grasped by hand, and used for rocking the lever in order to set it, as hereinafter described, for enabling the lever to be released by action of the thermostatic mechanism.

A tensile spring 12 is connected with the tripping lever 10 and with a supply pipe 13, with which the jet pipe 5 is connected, and through which gas is supplied to the jet pipe. The spring 12 is always under tension, and its tendency is to rock the lever 10 in a clockwise direction according to Figures 1 and 3, and thus to maintain this valve 8 in such condition that no gas can flow through it.

Mounted upon the mixing tube 5 and dis-

posed adjacent the valve 8 is a guide 14, and slidably extending through this guide and supported thereby is a locking bolt 15. This bolt is provided at one of its ends with an eye 16, and extending through this eye is a pivot pin 17. This pivot pin is carried by a thermostatic bar 18, and is rigid relatively thereto.

The thermostatic bar 18 has a general arcuate form, as indicated in Figure 1. It is mounted upon a boss 19 of angular form, as indicated in Figure 1, so as to be unable to rock or to have any lost motion relatively to this boss.

The thermostatic bar is thus rigid relatively to its mounting upon the boss, but has a limited swaying movement, as indicated by full and dotted lines in Figure 1, due to the expansion and contraction of the bar.

The thermostatic bar 18 is heated by the burner, and when thus heated assumes and maintains the position indicated for the bar by dotted lines in Figure 1. When, however, the thermostatic bar is no longer heated by the burner, it assumes the position indicated for it by full lines in Figure 1. Thus the sliding bolt 15 is thrust to the left according to Figure 1 whenever the burner is heated, and to the right according to this figure whenever the burner is cooled.

The locking bolt 15 is disposed adjacent the path of travel of one end of the lever 10, so that when this lever is rocked in a counter clockwise direction according to Figure 1 and thus brought into the position indicated for it by dotted lines in this figure, it may be held in this position by the locking bolt 15, provided this bolt is thrust endwise to the left according to this figure. This leaves the valve 8 and the various movable parts immediately associated therewith in the positions indicated for them in Figure 3.

With the parts in the positions just described, the gas is flowing freely through the valve 8, but is nevertheless subject to control by the manually operated valve 7. Assuming the parts to be in the positions here contemplated, and as indicated in Figure 3, the operator may grasp the handle 9, and by turning it into different positions may control with any degree of nicety the amount of gas flowing into the burner.

Suppose, now, that the two valves and

various movable parts associated therewith are in the positions contemplated by Figure 3, and that a sudden gust of wind extinguishes the flame of the gas burner. The result is that the thermostatic bar 18 now quickly cools off, and in so doing actuates the locking bolt 15, so that the thermostatic bar and the locking bolt move from the positions indicated for them by dotted lines in Figure 1 to the positions indicated for them by full lines in this figure. The locking bolt 15 is thus drawn out of engagement with the lever 10, and the latter is by tension of the spring 12 rocked in a 15 clockwise direction according to Figure 1, from the position indicated by dotted lines to the position indicated for it by full lines, in this figure. Hence the flow of gas through the jet pipe 6 is by action of the 20 valve 8 cut off abruptly, the action of the valve being practically automatic.

As may be readily seen, therefore, whenever the device is properly arranged and the gas burner is in action, if the burner flame 25 is extinguished by a sudden gust of wind or by any ordinary means in the nature of an accident, the flow of gas to the burner is cut off, abruptly and automatically.

The operation of my device may be readily understood from the foregoing description.

In order to use the burner, the operator proceeds as follows: By turning the handle 9 into the position indicated for it in Figure 1, the valve 7 is opened. The operator now grasps the lever 10, preferably using the portion 11 thereof as a handle, and rocks this lever into the position indicated for it by dotted lines in Figure 1. Gas now flows 40 freely to the burner. The operator next lights the gas flowing from the burner, and meanwhile holds the lever 10 in the position indicated for it by dotted lines in Figure 1. The heat from the burner affects the thermostatic bar 18 as above described, and by 45 so doing causes the locking bolt 15 to be thrust partially in the path of the lever 10. The operator now releases this lever, which thereupon presses sidewise upon the locking bolt 15 and is by this bolt prevented from turning.

The apparatus remains in this condition for any length of time, or in other words, so long as the burner remains in action. As 55 soon, however, as the burner flame is extinguished by a gust of wind or the like, the lever 10 is released as above described, and the valve 8 instantly stops the flow of gas to the burner.

Whenever the flow of gas is thus cut off the operator may as a precaution grasp the handle 9, and by turning it place the valve 7 in such condition that this valve alone would be sufficient to prevent the passage 65 of gas to the burner.

As indicated in the foregoing description, there is no interference between the control of the gas by means of the manually operated burner and by means of the burner under thermostatic control. That is to say, 70 the operator can regulate the gas flow by means of the manually operated valve in practically the same manner as if the valve 8 and the thermostatic mechanism were done away with altogether; and the valve 75 8, under thermostatic control will cut off the supply of gas flowing to the burner, notwithstanding anything the operator may do, accidentally or otherwise, to the manually operated burner.

I do not limit myself to the particular mechanism illustrated and described, as variations may be made therein without departing from my invention the scope of which is commensurate with my claims.

I claim:

1. A device of the character described comprising a gas burner, a mixing tube connected therewith, a jet pipe extending into said mixing tube for supplying gas through 90 said mixing tube to said burner, a valve mounted upon said jet pipe for opening and closing the same, a lever mounted upon said valve and movable into two normal positions, one for closing said valve and the other for keeping said valve open, a spring mechanism connected with said lever and always under tension for the purpose of closing said valve, a bolt slidably mounted upon said mixing tube and provided with 1 a portion extending partially into the path of travel of said lever, for the purpose of locking said lever in position to allow gas to flow freely through said valve, said bolt being for this purpose movable in the general direction of its own length and being the sole means required for locking said lever, and a thermostatic bar connected with said bolt for the purpose of actuating said bolt, said thermostatic bar having a general arcuate form and being curved partially around said gas burner, said thermostatic bar being controllable by temperature of said burner for the purpose of actuating said bolt.

2. A device of the character described comprising a burner, a mixing tube leading to said burner, a jet pipe for supplying gas to said mixing tube and thus to said burner, a valve mounted upon said jet pipe for opening and closing the same, a lever carried by said valve and movable into two normal positions, one for closing said valve and the other for keeping said valve open, a spring carried by said lever and always under tension for the purpose of closing said valve, a guide mounted upon said mixing tube, a bolt extending through said guide and slidably relatively thereto, said bolt being movable partially into the path

of travel of said lever for the purpose of locking said lever in the position to allow gas to flow, said bolt being the sole means required for locking said lever, and being for this purpose movable in the direction of its own length, and a thermostatic bar connected with said bolt for the purpose of thrusting said bolt lengthwise, said thermostatic bar having a general arcuate form and being curved partially around said gas burner, said thermostatic bar being mount- ed rigidly upon said burner at the end of said thermostatic bar opposite the end thereof connected with said bolt, said thermostatic bar being controllable by temperature of said burner for the purpose of actuating said bolt. 15

Signed at Akron, in the county of Summit and State of Ohio, this 10th day of November, 1923.

LOUIS HILL.
